CLAIM

The ornamental design for a dental expectorant basin, as shown.

DESCRIPTION

FIG. 1 is a perspective view taken from the front left side of the dental expectorant basin of the present invention;

FIG. 2 is a front view of the dental expectorant basin of FIG. 1;

FIG. 3 is a side view of the dental expectorant basin taken from the left side of FIG. 2;

FIG. 4 is a rear view of the dental expectorant basin of FIG. 1;

FIG. 5 is a side view of the dental expectorant basin taken from the right side of FIG. 2; and,

FIG. 6 is a top plan view of the dental expectorant basin of FIG. 1.
